UNITED STATES PATENT OFFICE.

SILAS O. BROWN, OF SULPHUR SPRINGS, TEXAS.

COTTON-CHOPPER ATTACHMENT FOR CULTIVATORS.

Application filed April 6, 1922. Serial No. 550,076.

To all whom it may concern:

Be it known that I, SILAS O. BROWN, a citizen of the United States, residing at Sulphur Springs, in the county of Hopkins and State of Texas, have invented new and useful Improvements in Cotton-Chopper Attachments for Cultivators, of which the following is a specification.

The object of my said invention is the provision of a simple, durable, efficient and easily manipulated cotton chopping attachment, designed to operate and be handled between the gangs and under the seat of a cultivator.

To the attainment of the foregoing, the invention consists in the improvement as hereinafter described and definitely claimed.

In the accompanying drawings, forming part of this specification:—

Figure 1 is a vertical cross section of a cultivator equipped with my novel attachment.

Figure 2 is a detail perspective of my novel attachment.

Figure 3 is an enlarged detail section hereinafter explicitly referred to.

Similar numerals of reference designate corresponding parts in all of the views of the drawings.

The cultivator in general is of the ordinary well known construction and includes a main frame 1, a driver's seat 2, gangs 3, an arched axle 4 and ground wheels 5, mounted on the spindles of the said axle 4.

In furtherance of my invention an internally toothed gear 6 is attached to one of the ground wheels 5, and a transverse shaft 7 is journaled in appropriate bearings 8, attached to the upright portions of the arched axle 4, Figure 1. At one end the said shaft 7 carries a spur gear 9 that is intermeshed with the internal gear 6 as illustrated.

Appropriately fixed on the shaft 7 at about the center thereof, is a beveled gear 10, and pendent from and adapted to swing forwardly and rearwardly on the said shaft 7 is a sleeve 11. Journaled in the said sleeve 11 is an upright shaft 12 having at its upper and lower ends beveled gears 13 and 14, respectively, the beveled gear 13 being intermeshed with and adapted to derive motion from the beveled gear 10.

Carried by the sleeve 11 is a rearwardly

extending and downwardly extending beam 55 15 on which are handles 16. Interposed between the said beam 15 and loop-shaped arm 17 on the bearing sleeves 8 is a retractile spring 18.

Journaled in the forward and rear portions 19 and 20 of the beam 15 is a longitudinal shaft 21 on which are carried chopping blades 22. At its forward end the said shaft 21 is equipped with a beveled gear 23 that is intermeshed with the before mentioned beveled gear 14 on the shaft 12.

In virtue of the construction described it will be manifest that the beam 15 is capable of being readily swung from side to side and is also capable of being conveniently swung 70 upwardly and downwardly with the result that the attendant who grasps the handles 16 is enabled to manipulate the chopper to the best advantage.

It will be readily apparent from the foregoing that my novel attachment is susceptible of being readily installed in cultivators such as at present in use, see the clamps 8*, and is also adapted to be incorporated in new cultivators at the time of manufacture 80 thereof.

I have entered into a detailed description of the construction and relative arrangement of the parts embraced in the present and preferred embodiment of my invention in order to impart a full, clear and exact understanding of the said embodiment. I do not desire, however, to be understood as confining myself to the said specific construction and relative arrangement of parts inasmuch as in the future practice of the invention various changes and modifications may be made such as fall within the scope of my invention as defined in my appended claim.

Having described my invention, what I claim and desire to secure by Letters Patent, is:—

In a cotton chopper, the combination of an arched axle, ground wheels thereon, a gear carried by one of said ground wheels, a transverse shaft journaled in bearings on the upright portions of the arched axle and bearing a gear intermeshed with the first-named gear, a pendent swinging sleeve connected with said transverse shaft, a miter gear fixed to said shaft, an upright shaft journaled in the sleeve and having a miter gear intermeshed with the first-named miter

gear, an additional miter gear on the lower portion of the shaft, a beam connected with said sleeve and capable of being swung laterally, handles on said beam, a retractile spring connected with the beam and adapted to yieldingly support the same, and a longitudinal shaft journaled in the beam and

equipped with chopping means and having a beveled gear intermeshed with the beveled or miter gear at the lower end of the upright ¹⁰ shaft.

In testimony whereof I affix my signature.

SILAS O. BROWN.
